[57] CLAIM

The ornamental design for a printer, as shown and described.

DESCRIPTION

FIG. 1 is a top, front, left side perspective view of the first embodiment of a printer showing our new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a right side elevational view thereof;

FIG. 7 is a top, front, left side perspective view of the second embodiment of our new design, the difference being an enlarged left side;

FIG. 8 is a front, elevational view thereof;

FIG. 9 is a rear elevational view thereof;

FIG. 10 is a left side elevational view thereof and the right side is identical to FIG. 6; and,

FIG. 11 is a top plan view thereof.
